UNITED STATES PATENT OFFICE

WILLIAM A. SMITH, SR., OF EASTON, PENNSYLVANIA, ASSIGNOR TO INGERSOLL-RAND COMPANY, OF JERSEY CITY, NEW JERSEY, A CORPORATION OF NEW JERSEY

ROCK DRILL

Application filed December 8, 1928. Serial No. 324,726.

This invention relates to fluid actuated tools, but more particularly to a fluid actuated rock drill in which the hammer piston reciprocates independently of the working implement which it is adapted to actuate.

One object of the invention is to assure thorough lubrication of the cooperating surfaces of the chuck mechanism and the element whereby it is guided, such as the front head of the rock drill.

Another object is to enable lubricant to be supplied to the surfaces in a rock drill in which the interior of the chuck mechanism is vented to the atmosphere so that the lubricant will have to be conveyed forwardly of the vented portion of the chuck mechanism.

Other objects will be in part obvious and in part pointed out hereinafter.

In the drawings illustrating one form which the invention may assume in practice and in which similar reference characters refer to similar parts,

Figure 1 is a longitudinal sectional elevation of a rock drill constructed in accordance with the practice of the invention,

Figure 2 is a transverse view taken through Figure 1 on the line 2—2 looking in the direction indicated by the arrows, and

Figure 3 is a similar view taken through Figure 1 on the line 3—3 looking in the direction indicated by the arrows.

Referring more particularly to the drawings, A designates a cylinder having a piston chamber B in which is disposed a reciprocating hammer piston C. The cylinder A has a free exhaust port A' which is controlled by the piston C. A back head D is disposed on the back end of the cylinder A and on the front end of the cylinder is a front head E. The cylinder A, the front head E and the back head D form the casing of the drill and are held in operative relationship by side bolts F disposed on opposite sides of the drill.

At the rearward end of the piston chamber B is an enlarged bore G for the reception of a valve box generally designated by H and comprising in this instance a pair of plates J and K. The valve box H forms a

closure for the rearward end of the piston chamber B and the plate J is suitably recessed to form a valve chamber L in which is disposed a distributing valve O of the oscillatory plate type.

In the plate K are formed inlet passages P and Q which are controlled by the valve O. The inlet passage P opens directly into the rearward end of the piston chamber B and the inlet passage Q which is a front inlet passage extends through both the plate K and through the cylinder A to the front end of the piston chamber B wherewith it communicates through a port R.

The plates J and K are provided with bores S and T respectively for the reception of a rifle bar U. The contiguous portions of the bores S and T may be enlarged to receive a bushing V which encircles the rifle bar U at this point and also extends through an aperture W in the valve O. The bushing V thus serves to prevent leakage of pressure fluid from the valve chamber L along the rifle bar into the rearward end of the piston chamber B.

In the construction shown, the plate J acts as a seat for a ratchet ring X which is disposed in the rearward end of the bore G and encircles a head Y of the rifle bar U and which head carries spring pressed pawls Z adapted to cooperate with the ratchet ring X in a well known manner for imparting rotary movement to the piston.

The valve box H, the ratchet ring X and the rifle bar U are held in the bore G by the back head D and to this end the back head D is provided with a flange b which seats on the ratchet ring X and forms one side of a supply reservoir c in the back head D.

Pressure fluid for actuating the piston C may be conveyed from a source of supply to the back head through a connection (not shown) but the point at which it may be attached to the back head D is indicated by a throttle valve chamber d in which is disposed a throttle valve e. The throttle valve e has a central bore f into which the pressure fluid may be introduced and has a port j in one side which, when the throttle valve e is in its open position, will register with a passage k

in the back head D and opening into the supply reservoir c.

In the ratchet ring X and the plate J are supply passages o which afford communication between the supply reservoir c and the valve chamber L. In the present instance however, a supply chamber p is formed in the plate J adjacent the valve L and the supply passages o open into the said supply chamber p for constantly supplying pressure fluid thereto.

The piston C is of the differential type and as shown has a fluted forward extension q which is guided slidably by a bore r in a front cylinder washer s which acts as a closure for the front end of the piston chamber B. The front cylinder washer s has an annular sleeve or extension t at the front end of which is a lateral flange u which lies between the adjacent ends of the cylinder A and the front head E and between which element said flange W is clamped to hold the front cylinder washer s securely in position.

The interior surface v of the extension t acts as a guiding surface for one end of the chuck w. The chuck also extends into a bore x in the front head E whereby it is guided at its forward end. In the rearward end of the chuck w is threaded a chuck nut y which may be suitably fluted to interlock slidably with the fluted extension q of the piston C.

The forward end of the chuck w is provided with clutch members z adapted to lock with similar clutch members 2 of a chuck driver 3 disposed in the front end of the bore x. The chuck driver 3 may be provided with the usual ribs 4 to interlock with wings 5 carried by a working implement 6 which extends into cavity 7 in the chuck w to receive the blows of the hammer piston C. The rearward end or shank 8 of the working implement 6 extends into and is guided by a chuck bushing 9 fitted into the forward end of the chuck w.

In order to prevent the passage of any pressure fluid which may leak past the piston extension into the working implement and thence through the working implement into the drill hole which, as is well known, is objectionable in certain localities where, because of the peculiar nature of the rock being drilled, the dust resulting from drilling when inhaled has been found to be injurious to the health of the operators, the front cylinder washer s is provided with an internal annular recess 10 which encircles the fluted portion of the piston C and communicates with the atmosphere through a port 11 in the front cylinder washer and the cylinder A. Due to this arrangement any pressure fluid which may leak past the piston extension q will be intercepted by the recess 10 and will then be exhausted to the atmosphere. Similarly the chuck cavity 7 is vented to the atmosphere through a port 12 leading from the chuck

cavity to the atmosphere to provide an avenue of escape for any pressure fluid which may flow from the rearward end of the piston chamber B through the piston and into the chuck cavity 7.

As is well known, in modern drilling practice it is customary to constantly supply lubricant to the various surfaces of the relatively movable parts of a rock drill by conveying the lubricant thereto through the medium of the pressure fluid utilized for actuating the drill. Lubricant may be introduced into the pressure fluid in various manners. One method which has met with considerable favor is to dispose an air line oiler in the pressure fluid supply line and introduce the lubricant into the main pressure stream in suitable form and quantities to supply the requirements of the rock drill. Another method frequently employed for accomplishing this purpose is to provide the drill with means embodied in itself to supply such lubricant as may be required for the best operation of the drill. One of the latter devices is incorporated in the drill illustrated and comprises a reservoir 13, for lubricant such as oil, formed in the periphery of the front cylinder washer s and for which the wall of the cylinder A forms an outer bounding surface. The lubricant may be introduced into the reservoir 13 through a filling opening 14 in the cylinder A normally sealed by a filler plug 15.

For the sake of simplicity of illustration, the lubricating system shown is intended to supply lubricant to the various portions of the rock drill only immediately prior to the starting of each period of operation of the drill. To this end the cylinder A is provided with a passage 16 which communicates at its front end with the reservoir through passages 17 in the cylinder A and the front cylinder washer s. The passage 16 extends rearwardly through the cylinder A and communicates in this instance with a supply passage o through a port 18 in the cylinder A and the rotation ratchet X so that when the throttle valve e is opened to supply pressure fluid to the drill pressure fluid will at the same time be admitted into the reservoir 13 to exert a pressure on the oil therein.

Owing to the fact that the reservoir 13 is remotely located from the point, such as the port 18 through which pressure fluid is admitted into the reservoir, there will be no oil conveyed from the reservoir into the main pressure fluid stream during the normal operation of the drill. However when the throttle valve e is closed to cut off the supply of pressure fluid to the valve chamber L the pressure fluid which has previously been entrapped in the reservoir and the passage leading thereto will also be exhausted into the valve chamber L and will carry with it a portion of oil sufficient to lubricate the

movable parts of the drill such as the piston and the valve preparatory to the subsequent drilling operation. Obviously, a considerable portion of oil will then remain in the valve chamber L and when the drill is again set in operation, such oil will be blown from the valve chamber and will pass through the inlet passages P and Q to the ends of the piston chamber B.

In order to assure an adequate quantity of lubricant to the cooperating surfaces of the chuck mechanism such as the chuck *w* and the chuck jaw 3 and the elements whereby they are guided as the bore *x* of the front head and the surface *v* of the extension *t*, the cylinder, the flange *u* and the front head E are provided with a passage 19 which leads from the forward extremity of the inlet passage Q to a point near the front end of the front head E. In the front head E are a pair of ports 20 and 21 which branch from the passage 19 and open into the bore *x*. Similarly in the front portion of the cylinder A is a passage 22 which leads from the passage 19 through the extension *t* to lubricate the surface of the rearward portion of the chuck *w*.

To insure a proper distribution of the oil flowing through the inlet passage Q between the front end of the piston chamber B and the chuck mechanism a restricted port 23 is formed between the passage 19 and the inlet passage Q to avoid an excess of oil to the chuck mechanism and a reduction in the supply of the oil to the front end of the piston chamber B.

As explained, the connecting port 23 between the inlet passage Q and the passage 19 will serve to supply oil to the chuck mechanism through these channels only immediately prior to each drilling operation. It may however be desirable that oil in suitable quantities be constantly supplied to the chuck mechanism and in order to secure this result the front cylinder washer *s* is provided with an annular groove 24.

The groove 24 is preferably located slightly in advance of the forward passage 17 so that the pulsations occurring in the reservoir 13 will force oil from the forward passage 17 between the cooperating surfaces of the front cylinder washer *s* and the cylinder A into the groove 24 from whence it will flow into the passage 19 through a connecting passage 25. The amount of oil thus conveyed from the reservoir into the groove 24 may be readily controlled by the degree of clearance between the front cylinder washer and the supporting surface of the piston A or by the spacing of the groove 24 and the passage 17.

The present invention has been found to be well adapted for supplying lubricant to the chuck mechanism of rock drills, particularly in drills where, as in the present in-

stance, the chuck cavity and other interior portions of the drill are vented to the atmosphere. Heretofore, it has been found to be an exceedingly difficult matter to lubricate the element forwardly of the vented portions of the drill. In fact the life of these parts in drills as formerly constructed has invariably been short. This was due to the fact that any lubricant which was conveyed by the pressure fluid flowing past the fluted extension of the piston was immediately exhausted to the atmosphere without any appreciable amount of it being deposited on the relatively movable surfaces of the chuck mechanism and the stationary parts of the drill. The present invention forms a convenient means of providing adequate lubricant to the chuck mechanism and has been found to greatly prolong the life of these parts both in rock drills of the vented type or those which are unvented.

The following is a brief description of the operation of the device: After the throttle valve *e* has been opened to set the percussive element of the drill in operation, pressure fluid will flow through the port 18 through the passage 16 and the ports 17 into the reservoir 13 to create a pressure therein on the oil. During the subsequent operation of the drill the pulsations occurring in the reservoir due to the admission and cut off of pressure fluid in the piston chamber B will force oil from the reservoir between the surfaces of the front cylinder washer and the cylinder to the groove 24.

From the groove 24 the oil will be conveyed through the medium of the pressure fluid existing in the passages 24 and 19 into and through the passages 22, 21 and 20 and will be delivered to the surfaces of the chuck *w* and the chuck jaw 3. Due to the pressure acting against these surfaces the oil will be suitably distributed longitudinally of the chuck mechanism. Any pressure fluid which may leak past the rearward end of the chuck *w* will find its way into the recess 10 and will then escape to the atmosphere through the port 11. Likewise such pressure fluid that flows from the ports 20 and 21 into the bore and which may find its way into the interior of the chuck mechanism will escape either through the forward end of the chuck jaw 3 or will flow rearwardly into the chuck cavity 7 from whence it will escape to the atmosphere through the port 12.

When the throttle valve *e* is closed to stop the drill and the pressure fluid existing between the throttle valve and the valve chamber will be exhausted therefrom the pressure fluid in the reservoir 13 will then escape through the passage 16 and the port 18 and through the supply passage wherewith it is connected into the valve chamber L. This pressure fluid will carry with it oil which will be deposited in the valve chamber.

and when the drill is again set in operation the inrushing pressure fluid will blow the oil from the valve chamber through the inlet passages both into the piston chamber and through the passages connecting the front inlet passage with the chuck mechanism.

I claim:

1. In a fluid actuated rock drill, the combination of a cylinder and a front head having a bore, a valve chamber, a distributing valve in the valve chamber, means for supplying lubricant to the valve chamber, a chuck in the bore, and a passage in the cylinder and the front head leading from the valve chamber for conveying lubricant from the valve chamber to the cooperating surfaces of the chuck and the bore, said passage being controlled by the valve.
2. In a fluid actuated rock drill, the combination of a cylinder and a front head having a bore, a valve chamber, a distributing valve in the valve chamber, means for supplying lubricant to the valve chamber, inlet passages leading from the valve chamber to the cylinder to convey pressure fluid and entrained lubricant to the cylinder, a chuck in the bore, and a passage in the cylinder and the front head associated with one inlet passage for conveying lubricant to the cooperating surfaces of the bore and the chuck.
3. In a fluid actuated rock drill, the combination of a cylinder and a front head having a bore, a valve chamber, a distributing valve in the valve chamber, means for supplying lubricant to the valve chamber, a front inlet passage and a rearward inlet passage leading from the valve chamber to the cylinder to convey pressure fluid and entrained lubricant from the valve chamber to the cylinder, a chuck in the bore, and a passage leading from the front inlet passage to the bore to convey lubricant to the cooperating surfaces of the bore and the chuck.
4. In a fluid actuated rock drill, the combination of a cylinder and a front head having a bore, a chuck in the bore, a valve chamber, a valve in the chamber, means for introducing lubricant into the valve chamber, and a passage leading from the valve to the bore and controlled by the valve for intermittently conveying pressure fluid and entrained lubricant from the valve chamber to the cooperating surfaces of the chuck and the bore.

In testimony whereof I have signed this specification.

WILLIAM A. SMITH, Sr.
